UNITED STATES PATENT OFFICE.

JULES HALTENBERGER, OF INDIANAPOLIS, INDIANA, ASSIGNOR TO JULES HALTENBERGER, INCORPORATED, OF INDIANAPOLIS, INDIANA, A CORPORATION OF INDIANA.

INTERNAL-COMBUSTION ENGINE.

Application filed April 29, 1927. Serial No. 187,428.

This invention relates to sleeve-valve engines of the type in which the sleeve-valve is provided with driving mechanism which imparts to it a movement combining axial reciprocation and circumferential oscillation such that any point on the sleeve follows a closed curved path. One form of drive for imparting such a movement to the sleeve is shown in my prior Patent No. 1,090,147 issued March 17, 1914.

In that patent, the sleeve is shown as being driven from an eccentric rotatable on an axis transverse to that of the sleeve, the movement of such eccentric being transmitted to the sleeve-valve through the medium of a connecting rod pivotally attached to the sleeve on an axis parallel to the sleeve axis. By this form of drive a movement having both axial and rotary components is imparted to the sleeve in order to secure the opening and closing of the inlet and exhaust ports.

The form of drive illustrated in my prior patent above referred to operates satisfactorily; but its reciprocating parts are comparatively heavy, and when it is employed on a multi-cylinder engine in which the sleeve-valves respectively surround the engine pistons, it necessitates spacing of the engine cylinders a greater distance apart than would otherwise be necessary. It is the object of my invention to produce a sleeve-valve drive having light-weight reciprocating parts, such drive being of the general type shown in my prior patent and adaptable for use in multi-cylinder engines in which the distance between adjacent cylinders is reduced to a minimum. Another object of my invention is to produce such a drive in which the sleeve-valve connecting rod is pivotally attached to the sleeve on an axis located as close as practicable to the axis of the sleeve in order to secure a maximum circumferential movement of the sleeve with a given eccentric throw or to secure a minimum eccentric throw for a given circumferential movement of the sleeve. Still another object of my invention is to produce such a drive in which adequate bearing areas are provided for transmitting the thrust which results in axial movement of the sleeve. A further object of my invention is to provide a con-

struction in which the sleeve and the parts which drive it may be quickly assembled and disassembled. A still further object of my invention is to produce a construction in which the sleeve is axially adjustable relative to the driving mechanism in order to obtain variations in valve timing or to correct any inaccuracies of manufacture.

I accomplish the above objects by providing in the engine embodying my invention a sleeve-valve operating shaft which, in a four-cycle engine, is driven from the crank shaft at half engine speed and which extends in a plane parallel to the plane of the cylinders. This operating shaft is provided with an eccentric crank for each of the sleeves, such sleeves being located in their respective engine cylinders. On each of these cranks I mount a connecting rod which is pivotally attached to the associated sleeve on an axis parallel to that of the sleeve so that rotation of the crank will produce both axial reciprocation and circumferential oscillation of the sleeve.

The accompanying drawings illustrate my invention: Fig. 1 is a horizontal section through a multi-cylinder engine on the line 1—1 of Fig. 2 with some parts broken away; Fig. 2 is a vertical section on the line 2—2 of Fig. 1; Fig. 3 is a fragmental horizontal section similar to Fig. 1, but on an enlarged scale on the line 3—3 of Fig. 4; Fig. 4 is a side elevation of the lower end of one of the sleeves and its associated connecting rod; Fig. 5 is a horizontal section on the line 5—5 of Fig. 6 showing a modified form of connecting rod; Fig. 6 is a side elevation of the lower end of the sleeve and connecting rod shown in Fig. 5; Fig. 7 is a fragmental horizontal section generally similar to Fig. 1 but on a larger scale and illustrating another modification of my invention; Fig. 8 is a section on the line 8—8 of Fig. 7, showing in elevation the lower end of the sleeve; and Fig. 9 is a fragmental elevation of the end of the connecting rod embodied in the drive shown in Figs. 7 and 8.

In the construction illustrated in Figs. 1 and 2 there are a plurality of engine cylinders 100 each of which is provided with a sleeve-valve 11. Within each of the sleeve valves

- 11 there is a piston (not shown), such pistons being respectively connected by connecting rods 12 to crank pins 13 on the engine crank shaft. Located at about the height of 6 the lower end of the sleeves 11 and extending parallel to the crank shaft and the plane of the cylinders 10 is a sleeve-valve operating shaft 15 provided with an eccentric 16 for each of the sleeves 11.
- 10 Mounted on each of the eccentrics 15 is a sleeve connecting rod 18 which extends inward toward the cylinders and is pivotally attached to the associated sleeve on an axis parallel to that of such sleeve. In addition 15 to being pivotally attached to its associated sleeve, each of the connecting rods 18 is so mounted in the sleeve that its position axially of the sleeve is fixed, in order that rotation of the operating shaft 15 through 20 the eccentric 16 will impart to such sleeve a movement having both axial and circumferential components.

In the construction illustrated in Figs. 1, 2, 3, and 4, the sleeve 11 is provided with an 25 outwardly extending boss 20 in which is a screw-threaded hole disposed parallel to the sleeve axis. The outer end of the boss 20 may be cut off so that its distance from the center of the screw-threaded hole is less than 30 the radius of such hole, as is clear from Fig. 3. Further, the outer end of the boss 20 may be convexly curved concentric with the bore of the sleeve 11 in order that such boss will clear the sleeve in the adjacent cylinder. 35 Adapted to be received in the screw-threaded hole in the boss 20 is a screw-threaded member 21, such member being flattened on opposite sides in order that it may be inserted laterally into the hole in the boss 20. 40 The connecting rod 18 is desirably bifurcated at its inner end, the ends of such bifurcations being provided with projections 23 adapted to be inserted in transverse holes in a member 21. After the projections 23 are 45 inserted in the transverse holes of the member 21, they may be permanently secured therein by being riveted as is clear from Fig. 4.

The connecting rod 18 after being 50 cured to the threaded member 21 may be attached to the sleeve 11 by holding it in the dotted line position shown in Fig. 3, inserting the threaded member 21 laterally into the hole in the boss 20 and rotating the sleeve 55 to the full line position shown in Fig. 3. A reversal of these steps will enable the connecting rod to be disconnected from the associated sleeve.

From the above description of the 60 construction, it will be apparent that rotation of the operating shaft 15 will cause each of the sleeves 11 to move with both axial reciprocation and circumferential oscillation. The circumferential oscillation of each of the 65 sleeves causes the axis of attachment of such

sleeve and its associated connecting rod 18 to move longitudinally of the shaft 15, and some provision must be made for permitting such movement. To this end, I have shown in Figs. 1 and 2 split bushings 25 mounted 70 on each of the crank pins 16, such bushings being provided exteriorly with a spherical surface which mates with a complementarily shaped surface in the associated connecting rod 18. This construction permits each connecting rod 18 to swing about a vertical axis on its associated bushing 25, thus allowing for the longitudinal displacement of the inner end of the connecting rod in the circumferential oscillation of the sleeve 11. 75

Another means for providing for longitudinal movement of the inner end of the connecting rod 18 is shown in Figs. 3 and 4. In this construction, the connecting rod 18 is provided with an enlarged bearing portion 80 18' which receives the associated eccentric crank 16 of the bearing shaft 15. The bearing portion 18' is made shorter in length than the crank 16 in order that it may slide thereon as circumferential oscillation of the associated sleeve 11 occurs.

In Figs. 5 and 6 I have illustrated a modification of my invention in which another means is employed for attaching the connecting rod 18 to its associated sleeve. In this 85 construction, the sleeve 11 is provided at its lower end with a projecting boss 28 which has extending through it a cylindrical hole parallel to the axis of the sleeve. The outer face of this boss 28 is convexly curved as is 90 the corresponding face of the boss 20, and the hole in the boss 28 may be spaced from such outer face a distance less than the radius of such hole as is clear from Fig. 5. The inner face of the connecting rod 18 is bifurcated 95 and provided with projections 23 which are employed to attach to the connecting rod a cylindrical member 29 having its opposite faces flat in order that it may be inserted laterally into the hole in the boss 28. 100

To provide for the necessary thrust connection between the sleeve 11 and the connecting rod 18, the member 29 is provided intermediate its ends with a laterally extending flange 30 which is received in a transverse 110 groove 31 in the boss 28. To assemble the connecting rod 18 and the associated sleeve 11, the rod is held in the dotted-line position shown in Fig. 5, and the member 29 is 115 inserted into the hole in the boss 28, the flange 30 at the same time entering the groove 31 which has a depth sufficient to permit such movement. In making the groove 31 of this depth, it may communicate with the interior 120 of the sleeve 11 (as it does in the construction shown in Fig. 5) but this is not objectionable. After the member 29 is inserted into the boss 28 with the connecting rod 18 in the dotted-line position shown in Fig. 5, the connecting rod is revolved about the axis of the member 125 130

29 to the full-line position shown in Fig. 5 and is then attached to the associated crank 16 of the operating shaft 15. The connecting-rod 18 may be mounted on its associated crank 16 either by the construction shown in Figs. 1 and 2 or by that shown in Figs. 3 and 4. A still further form of my invention is illustrated in Figs. 7, 8, and 9. In this construction, I employ a sleeve connecting rod 35 having its upper and lower faces plane and parallel, such connecting rod being received in the space between two outwardly projecting bosses 36 on the lower end of the sleeve 11. The bosses 36 have extending through them aligned holes parallel to the axis of the sleeve. The connecting rod 35 is provided on its upper and lower faces with aligned vertically extending projections 37. In the outer faces of the bosses 36, I provide a slot communicating with the vertical holes in such bosses, such slot having a width slightly greater than the diameter of the bosses 37 in order that such bosses may be inserted laterally into the holes in the boss 36. The bosses 37 are made of smaller diameter than the holes in which they are received, and after they are in place in such holes, bushings 38 are slipped over them, such bushings having an external diameter substantially equal to that in the holes in the bosses 36 and an internal diameter substantially equal to that of the projections 37. The bushings 38 may be held in place by means of screws 39 screw-threadedly mounted in the bosses 36. The connecting rod 35 may be attached to its associated operating crank 16 either by the method illustrated in Figs. 1 and 2 or by that shown in Figs. 3 and 4.

In all the various modifications I have illustrated and described, the interconnection of the sleeve and its connecting rod is provided by a pin rigid with the connecting rod, such pin being insertable into its hole in the sleeve-boss by lateral movement through an opening provided in the boss. In all the structures shown, the bearing surfaces on the connecting rod which transmit axial thrusts are located within the axial limits of the sleeve-boss. This is of advantage in case it is necessary (as in the structure shown in Figs. 5 and 6) to provide an opening through the sleeve; for by leaving the thrust surfaces below the upper axial limit of the boss, such opening is low enough not to interfere with the action of the piston. Further, the reciprocating parts of the drive are relatively light in weight, thus decreasing inertia forces.

The modification of my invention shown in Figs. 1 to 4 inclusive has an advantage over other forms in that the sleeve may be raised or lowered relative to the sleeve-connecting rod to correct for inaccuracies of manufacture or to vary the valve timing.

All the structures which I have illustrated and described have a particular advantage in

connection with the manner in which the parts are arranged to sustain the effect of the vertical force imposed on the sleeve connecting-rod by the eccentric 16. Such force has a tendency to rock the sleeve connecting-rod in a vertical plane about its point of attachment to the sleeve and must be opposed by a suitable arrangement of interengaging surfaces provided on the rod and sleeve. In the construction illustrated in my prior patent and in similar arrangements where the pin and sleeve connecting-rod are not rigid with each other, there inevitably occurs a certain "play" or lost motion between these parts as a result of the alternate upward and downward forces exerted on the end of the rod by the eccentric 16. Because of this "play", the effect of the force exerted by the eccentric is taken between the horizontal engaging faces of the rod and the boss on the sleeve. The continual reversal of these forces results in time in a spreading of the boss flanges which is avoided in my structure by having the pin rigid with the connecting-rod.

I claim as my invention:—

1. In an internal combustion engine, the combination of a cylinder, a piston reciprocable therein, a sleeve-valve surrounding said piston, a rotatable valve-operating shaft, an eccentric on said shaft, a boss on said sleeve, said boss being provided with a hole parallel to the sleeve axis, and a sleeve connecting rod for connecting said sleeve and said eccentric, said connecting rod including a pin rigid with the remainder of the rod and receivable in the hole in said boss, said connecting rod and boss having co-operating surfaces for transmitting thrusts axially of said sleeve, such thrust surfaces on said connecting rod being located within the axial limits of said boss.

2. In an internal combustion engine, the combination of a cylinder, a piston reciprocable therein, a sleeve-valve surrounding said piston, a rotatable valve-operating shaft, an eccentric on said shaft, a boss on said sleeve, said boss being provided with a hole parallel to the sleeve axis, and a sleeve connecting rod for connecting said sleeve and said eccentric, said connecting rod including a pin rigid with the remainder of the rod and receivable in the hole in said boss, said connecting rod and boss having co-operating surfaces for transmitting thrusts axially of said sleeve.

3. In an internal combustion engine, the combination of a cylinder, a piston reciprocable therein, a sleeve-valve surrounding said piston, a rotatable valve-operating shaft, an eccentric on said shaft, a boss on said sleeve, said boss being provided with a hole parallel to the sleeve axis, and a sleeve connecting rod for connecting said sleeve and said eccentric, said connecting rod including a pin rigid with the remainder of the rod and receivable in the hole in said boss, said connecting rod and

boss having co-operating surfaces for transmitting thrusts axially of said sleeve, the hole in said boss communicating with an exterior face of said boss through an opening 5 through which said pin may be laterally passed into and out of such hole, such opening having a width less than the diameter of such hole.

4. In an internal combustion engine, the combination of a cylinder, a piston reciprocable therein, a sleeve-valve surrounding said piston, a rotatable valve-operating shaft, an eccentric on said shaft, a boss on said sleeve, said boss being provided with a hole parallel 10 to the sleeve axis, and a sleeve connecting rod for connecting said sleeve and said eccentric, said connecting rod including a pin rigid with the remainder of the rod and receivable in the hole in said boss, said connecting rod 15 and boss having co-operating surfaces for transmitting thrusts axially of said sleeve, the hole in said boss communicating with an exterior face of said boss through an opening 20 passing through which said pin may be laterally passed into and out of such hole.

5. In an internal combustion engine, the combination of a cylinder, a piston reciprocable therein, a sleeve-valve surrounding said piston, a rotatable valve-operating shaft, an eccentric on said shaft, a boss on said sleeve, said boss being provided with a hole parallel 30 to the sleeve axis, and a sleeve connecting rod for connecting said sleeve and said eccentric, said connecting rod including a pin rigid with the remainder of the rod and receivable in the hole in said boss, said pin having a plurality of laterally projecting flanges 35 adapted to be received in grooves in said boss, said flanges and grooves being disposed helically. 45

6. In an internal combustion engine, the combination of a cylinder, a piston reciprocable therein, a sleeve-valve surrounding said piston, a rotatable valve-operating shaft, an eccentric on said shaft, a boss on said sleeve, said boss being provided with a hole parallel 50 to the sleeve axis, and a sleeve connecting rod for connecting said sleeve and said eccentric, said connecting rod including a pin rigid with the remainder of the rod and receivable in the hole in said boss, said pin having one or more laterally projecting flanges 55 adapted to be received in grooves in said boss. 60

7. In an internal combustion engine, the combination of a cylinder, a piston reciprocable therein, a sleeve-valve surrounding said

piston, a rotatable valve-operating shaft, an eccentric on said shaft, a boss on said sleeve, said boss being provided with a hole parallel 70 to the sleeve axis, and a sleeve connecting rod for connecting said sleeve and said eccentric, said connecting rod including a pin rigid with the remainder of the rod and receivable in the hole in said boss, said connecting rod and boss having co-operating surfaces for transmitting thrusts axially of said sleeve, the hole in said boss communicating with an exterior face of said boss through an opening 75 passing through which said pin may be laterally passed into and out of such hole, said pin having one or more laterally projecting flanges 80 adapted to be received in grooves in said boss. 85

8. In an internal combustion engine, the combination of a cylinder, a piston reciprocable therein, a sleeve-valve surrounding said piston, a rotatable valve-operating shaft, an eccentric on said shaft, a boss on said sleeve, said boss being provided with a hole parallel 90 to the sleeve axis, and a sleeve connecting rod for connecting said sleeve and said eccentric, said connecting rod including a pin rigid with the remainder of the rod and receivable in the hole in said boss, said pin having a plurality of laterally projecting flanges 95 adapted to be received in grooves in said boss, said flanges and grooves being disposed helically. 100

9. In an internal combustion engine, the combination of a cylinder, a piston reciprocable therein, a sleeve-valve surrounding said piston, a rotatable valve-operating shaft, an eccentric on said shaft, a boss on said sleeve, said boss being provided with a hole parallel 105 to the sleeve axis, and a sleeve connecting rod for connecting said sleeve and said eccentric, said connecting rod including a pin rigid with the remainder of the rod and receivable in the hole in said boss, said connecting rod and boss having co-operating surfaces for transmitting thrusts axially of 110 said sleeve, the hole in said boss communicating with an exterior face of said boss through an opening passing through which said pin may be laterally passed into and out of such hole, said pin having a plurality of laterally projecting flanges 115 adapted to be received in grooves in said boss, said flanges and grooves being disposed helically. 120

10. In an internal combustion engine, the combination of a cylinder, a piston reciprocable therein, a sleeve-valve surrounding said piston, a rotatable valve-operating shaft, an eccentric on said shaft, a boss on said sleeve, said boss being provided with a hole parallel 125 to the sleeve axis, and a sleeve connecting rod for connecting said sleeve and said eccentric, said connecting rod including a pin rigid with the remainder of the rod and receivable in the hole in said boss, said connecting rod and boss having co-operating 130

surfaces for transmitting thrusts axially of said sleeve, said connecting rod having a universal connection with said eccentric whereby it may swing relatively thereto about an axis 5 parallel to the axis of said sleeve.

11. In an internal combustion engine, the combination of a cylinder, a piston reciprocable therein, a sleeve-valve surrounding said piston, a rotatable valve-operating shaft, an eccentric on said shaft, a boss on said sleeve, said boss being provided with a hole parallel 10 to the sleeve axis, and a sleeve connecting rod for connecting said sleeve and said eccentric, said connecting rod including a pin rigid 15 with the remainder of the rod and receivable in the hole in said boss, said connecting rod having a universal connection with said eccentric whereby it may swing relatively 20 thereto about an axis parallel to the axis of said sleeve.

12. In an internal combustion engine, the

combination of a cylinder, a piston reciprocable therein, a sleeve-valve surrounding said piston, a rotatable valve-operating shaft, an eccentric on said shaft, and a connecting rod 25 mounted on said eccentric and pivotally attached to said sleeve, said sleeve and connecting rod being relatively adjustable axially of the sleeve.

13. In an internal combustion engine, a 30 sleeve valve, an operating shaft therefor, an eccentric on said shaft, and a connecting rod mounted on said eccentric and pivotally attached to said sleeve, said sleeve and connecting rod being relatively adjustable axially of 35 the sleeve.

In witness whereof, I have hereunto set my hand at Indianapolis, Indiana, this 25th day of April, A. D. one thousand nine hundred and twenty-seven.

JULES HALTENBERGER.
